UNITED STATES PATENT OFFICE.

FREDERIC COBLYN, OF SERAING, BELGIUM.

RAILWAY-CHAIR.

SPECIFICATION forming part of Letters Patent No. 431,138, dated July 1, 1890.

Application filed December 6, 1887. Serial No. 257,085. (No model.) Patented in Belgium February 19, 1886, No. 72,053; in France March 23, 1886, No. 174,959; in Germany March 28, 1886, No. 37,491; in Spain April 14, 1886, No. 9,214; in Luxembourg April 21, 1886, No. 675; in Austria-Hungary April 24, 1886, No. 19,852; in England September 1, 1886, No. 11,146; in Italy January 24, 1887, No. 21,149/480, and in Portugal April 18, 1888, No. 1,262.

To all whom it may concern:

Be it known that I, FREDERIC COBLYN, a citizen of the Kingdom of Belgium, and a resident of Seraing, Belgium, have invented certain new and useful Improvements in Railway-Chairs, (for which I have obtained Letters Patent in Belgium, dated February 19, 1886, No. 72,053; in Germany, dated March 28, 1886, No. 37,491; in England, dated September 1, 1886, No. 11,146; in Austria-Hungary, dated April 24, 1886, No. 19,852; in Spain, dated April 14, 1886, No. 9,214; in France, dated March 23, 1886, No. 174,959; in Luxembourg, dated April 21, 1886, No. 675; in Italy, dated January 24, 1887, No. 21,149/480, and in Portugal, dated April 18, 1888, No. 1,262,) of which the following is a full, clear, and exact specification.

Referring to the drawings, Figure 1 is a vertical transverse section of a portion of a metallic tie and rail and my improved rail-fastening devices. Fig. 2 is a horizontal section on line $\alpha\alpha$ of Fig. 1, and Fig. 3 is a side elevation, the tie being shown in section.

The invention relates to railway-chairs, and to means for securing the rail thereto and to the tie, and has for its object, not only to provide a secure fastening for the rail, but also to provide means for readily disconnecting the rail and replacing it when this becomes necessary.

The invention consists in the combination, with the tie and rail, of a chair of peculiar construction, a shoe, and a wedge, substantially as hereinafter described, and as set forth in the claims.

In the drawings, T indicates the tie, presumed to be of metal, though of course the ordinary wooden tie would answer as well.

C is the chair, whose bed-plate c is made tapering in the direction of the center of the track, and from which projects an abutment C', that has approximately the form of a truncated pyramid, and inclines in the direction of the rail R, which may be of any usual pattern.

S is a shoe, constructed in the form of a housing, and fits over the abutment and nearly incloses the same, except a portion of the

outer face thereof. The shoe has a central vertical and semi-cylindrical groove's', formed in the outer face of its inner wall s, for purposes presently explained, and said wall is of such height or length as to extend down to or nearly to the bed-plate of the chair.

P is a retaining or clamping plate bolted to the bed-plate c of the chair and to the tie T and overlaps a portion of the inner half of the foot of the rail R, and W is a wedge driven between the web r of the rail and the shoe S, and constitutes the means to lock the parts together. It is obvious that by driving out the wedge W the shoe S can be lifted off the abutment C' of the chair and the rail-foot then slipped from under the retaining or clamping plate, thus providing a rail-fastening which affords the facility of removing the rail without disturbing the chair or its fastenings. When a wedge of wood is employed and tightly driven between the shoe and web of the rail, it will expand into the semi-cylindrical groove's', formed in the inner face of the shoe, and thereby prevent its working loose, while if a metallic wedge is employed said wedge may be provided with a like groove and a bolt inserted into the hole so formed to prevent longitudinal displacement of the wedge.

As more plainly shown in Fig. 1, the lower end of the shoe S extends downward sufficiently far to lie against the foot of the rail, thus holding the latter against displacement toward the abutment of the chair should the wedge W accidentally work loose. The object of forming the inner face of the abutment inclined relatively to the web of the rail is to lock the shoe against vertical displacement, the inner wall of said shoe increasing in thickness from the cap s² or upper wall downwardly; and to more securely fasten the rail to the tie I form the surface of the shoe facing the rail also inclined relatively to the web of the rail, so that the wedge may be driven more tightly in and have a firm bearing against vertical displacement, the wedge locking the parts firmly together. If desired, the retaining or clamping plate P may be cast in one piece with the chair.

The object of forming the base or bed plate of the chair tapering is to give the tread of the rail R a slight inward inclination. This may, however, be effected by a proper construction 5 of the tie or by interposing a wedge-shaped plate between the chair and tie. It is of course a great convenience of construction to provide the chair with a bed-plate, yet this may be dispensed with and the abutment C' and 10 clamp P bolted separately to the tie, while instead of the clamp spikes may be used with wooden ties. On the other hand, the abutment may be of cylindrical form, the shoe S being constructed accordingly, so as to accommodate 15 itself to this form.

Having thus fully described my invention, what I claim as new, and desire to secure by Letters Patent, is—

1. The combination, substantially as herein 20 described, with a tie, a rail, and fastening devices for confining the rail-foot to the tie on one side of the rail, of an abutment projecting from the tie on the opposite side, a shoe adapted to fit onto said abutment and having 25 its face proximate to the rail inclined, and a wedge adapted to be driven between the web of the rail and the shoe, for the purpose specified.

2. The combination, substantially as herein 30 described, with a tie, a rail, and fastening devices for confining the rail-foot to the tie on one side of the rail, of an abutment projecting from the tie on the opposite side, a shoe adapted to fit onto the abutment and 35 having its face proximate to the rail inclined and abutting against the rail-foot, and a wedge adapted to be driven between the web of the rail and the shoe, for the purpose specified.

3. The combination, substantially as herein 40 described, with a tie, a rail, and fastening devices for confining the rail-foot to the tie on one side of the rail, of an abutment projecting from the tie on the opposite side of the rail, a shoe constructed to fit onto the 45 abutment, said shoe having its face proximate to the rail inclined and provided with a vertical groove or recess, and a wedge adapted to be driven between the web of the rail and the shoe, for the purpose specified.

50 4. The combination, substantially as herein described, with a tie, a rail, and fastening devices for confining the rail-foot to the tie on one side of the rail, of an abutment projecting vertically from the tie on the opposite 55 side of the rail and having its face proximate

to the rail inclined, a shoe constructed to fit on said abutment and increasing in thickness downwardly, and a wedge constructed to be driven into the space formed between the inclined face of the shoe and the vertical face 60 of the rail-web, for the purpose specified.

5. The herein-described rail-chair, comprising a base-plate, an abutment projecting vertically therefrom and at right angles thereto, in combination with a detachable shoe constructed to fit on the abutment and having its outer face inclined, substantially as and for the purpose specified.

6. The herein-described rail-chair, comprising a base-plate gradually decreasing in thickness and an abutment projecting vertically therefrom and at an angle thereto, in combination with a detachable shoe constructed to fit onto the abutment and having its outer face inclined, substantially as and for the purpose specified.

7. The herein-described rail-chair, comprising a base-plate provided on one side with a clamping-plate and on the opposite side with an abutment projecting vertically from and 80 at an angle to said base-plate, in combination with a detachable shoe constructed to fit on the abutment and increasing in thickness downwardly, substantially as and for the purpose specified.

8. The herein-described rail-chair, comprising a base-plate provided on one side with a clamping-plate P and on the opposite side with an abutment having the form of a truncated pyramid and projecting vertically from 90 and at an angle to said base-plate, in combination with a detachable shoe S, constructed to fit on the abutment and increasing in thickness downwardly, substantially as and for the purpose specified.

9. The herein-described rail-chair, comprising a base-plate P on one side thereof, an abutment C' on the opposite side projecting vertically from and at an angle to the base-plate, in combination with the shoe S, constructed as described and provided in its outer face with a vertical groove or recess, substantially as and for the purpose specified.

In testimony that I claim the foregoing I have hereunto set my hand this 6th day of July, 1887.

FREDERIC COBLYN.
